UNITED STATES PATENT OFFICE.

LAURITS M. NIELSEN, OF BOSTON, MASSACHUSETTS, ASSIGNOR TO AGNEW AUTO MAILING MACHINE COMPANY, OF BOSTON, MASSACHUSETTS, A CORPORATION OF MAINE.

FILE-DRAWER.

No. 859,831.

Specification of Letters Patent.

Patented July 9, 1907.

Application filed April 4, 1905. Serial No. 253,806.

To all whom it may concern:

Be it known that I, LAURITS M. NIELSEN, of Boston, in the county of Suffolk and State of Massachusetts, have invented certain new and useful Improvements 5 in File-Drawers; and I hereby declare that the following is a full, clear, and exact description of the same, reference being had to the accompanying drawings, forming part of this specification.

This invention relates to improvements in file 10 drawers and particularly to improvements in card file drawers adapted for the storage of address cards or forms.

One object of the invention is to so construct a file 15 drawer that the cards or forms contained therein may be moved endwise of the drawer and through an opening with which one end of the drawer is provided.

Another object of the invention is to so construct a file drawer of this nature that when said drawer is placed in the vertical position the cards, or forms, 20 therein may be fed automatically downward through a suitable opening in the, in said position, lower end of the drawer.

Other objects of the invention will appear from the following description.

25 The invention consists in the peculiar file drawer herein described.

The invention also consists in the novel follower for supporting and following the cards.

The invention also consists in such other novel features of construction and combination of parts as shall 30 hereinafter be more fully described and pointed out in the claims.

Figure 1, represents an end view of the improved file drawer. Fig. 2, represents a cross sectional plan view 35 of parts of the same taken on line 2—2, Fig. 1. Fig. 3, represents a longitudinal sectional view of portions of the improved drawer.

Similar numbers of reference designate corresponding parts throughout.

40 File drawers of this particular nature are designed for the storage of cards, address forms, or similar articles, which cards, address forms, etc., are to be removed from the drawer from time to time for use in a machine, in which the special construction of the particular article adapts it for use. One of the features of the drawer being that construction whereby the automatic feeding of the articles towards and through an opening in one end of the drawer is made possible.

In carrying this invention into practice I construct 50 a drawer, or drawer section, having inside dimensions capable of receiving the cards, address forms, or other articles, in the upright position and having the sides

5—5, the bottom 6, preferably having the slot 7, the rear end 8 and the forward end frame 9 secured to the sides 5—5 between which and the ends 9—9 are formed 55 the guide grooves 10—10; in the lower part of the frame 9 and in the end 8 is secured the rod 11 which is preferably located in the slot 7, whereby it is beneath the inner surface of the bottom 6.

60 In the guide grooves 10—10 is slidable the gate 12 having the thumb piece 13 and, preferably, furnished with the opening 14 through which the index or guide form A can be viewed.

On the rod 11 is slidable the follower 15 having the 65 perforated member 16, the perforation of which works freely on said rod when its walls are parallel to the extension of the rod 11 but which is designed to bind on the rod when the walls of its perforation are brought to a suitable angle with said rod, as by the swinging forward or backward of the upper end of this follower, this upper end portion of the follower being furnished with the projection 17 which is so proportioned to the direction of the perforation in the member 16 that, when the drawer is placed upright on the frame 9, said projection 70 bearing on the rear card, or form, B the relation of said perforation with respect to the rod 11 will be such that the follower 15 will follow the downward movement of the cards, or forms; and, in a degree, exert a pressure on said cards, or forms, to move them downward. 80 When, however, the follower is crowded against the stencil cards, or forms, the projection 17 effects the forcing backward of the free end of the follower whereby the binding of the walls of the perforation on the rod 11 is effected, thus the series of stencil cards may be 85 clamped between the follower and the gate 12 and the file drawer may be handled and even reversed in position without permitting the dropping out of any of the stencil cards.

The drawer is adapted to be placed in a suitable machine, not a part of the present invention, through which the cards, or forms, are designed to be fed to a similar drawer; when the gate 12 is opened, the drawer resting on the end 9, the guide card A and the following cards B—B move downward under their own weight 95 and the pressure of the follower 15 and are fed through the machine into a similar drawer in which they arrange themselves in succession the inscription on the guide card appearing through the opening 14 in the gate 12 of said drawer.

100 Having thus described my invention, I claim as new and desire to secure by Letters Patent—

1. A file drawer having an opening in the end, and a gate for closing the opening, said gate having an opening through which an index may be exposed to view.

105

2. A file drawer having a longitudinal guide, and a follower mounted to slide upon said guide, when in the upright position and to bind on said guide when inclined slightly from the sliding position, said follower having a projection adapted to bear against the rear article in said drawer to maintain the follower in the sliding position.

5 3. A file drawer having the open frame 9, and the guide grooves 10-10, and the rod 11, and the gate 12 to slide in the grooves 10-10, in combination with the follower 15,

having the perforated member 16, adapted to slide on the 10 rod 11, and the projection 17 at its upper end, as and for the purpose described.

In testimony whereof I affix my signature in presence of two witnesses.

LAURITS M. NIELSEN.
